WING ROTOR

Johannes Christiansen, Sorup-Schauby, Germany, assignor of one-half to Alfred Oberle, Washington, D. C.

Application October 28, 1931, Serial No. 571,649.
Renewed May 15, 1934. In Germany October 24, 1930

16 Claims. (Cl. 244—16)

This invention relates to improved means for moving conveyances of various description, whether on land, on water or in the air, and has for its object to provide a wing-rotor for flying vessels, and the arrangement of such rotors, especially in connection with aeroplanes.

The present invention does not make use of the "Magnus effect" and differs from Gyrocepters and the known type of screw rotors.

10 The principal differentiating feature and one of the salient objects of the invention consists in the construction and arrangement of two rigid planes, one of which is located near the center of the wing rotor, the other one constituting 15 the top or cover of the rotor.

15 The invention further consists of the novel construction, combination and arrangement of parts as hereinafter more specifically described and illustrated in the accompanying drawings, 20 wherein is shown an embodiment of the invention, it being understood that changes, variations and modifications can be resorted to within the scope of the claims.

25 Similar characters of reference indicate similar parts throughout the several views.

Figure 1 is a perspective front view of an aeroplane equipped with two laterally disposed wing-rotors.

Figure 2 is a perspective side view of Figure 1. 30 Figure 3 represents a longitudinal sectional view of a wing-rotor.

Figures 4, 5 and 6 represent cross-sectional views of different positions of a pendulum.

Figure 7 is a transverse sectional view of a 35 wing-rotor with a preferred form of the inner semi-circular rigid plane.

Figure 8 is a transverse sectional view of a wing-rotor with the inner rigid plane at a negative angle in regards to the upper or outer rigid 40 plane.

Figure 9 is a transverse sectional view of a wing-rotor when descending or falling.

Figure 9a is a cross-sectional view of the inner 45 rigid plane of a wing-rotor of a shape different from those illustrated in Figures 7, 8, 9 and 10.

Figure 10 shows a transverse sectional cut through two rotors arranged in series, one behind the other.

In Figures 11 and 12 a modification of the device 50 is shown in which a vertical, power-driven, rotating shaft is provided at each side of the body and a plurality of rotor devices are mounted on each shaft.

Figure 11 is a plan view of a "lift vessel" of 55 the gyro type equipped with wing-rotors.

Figure 12 is a front view of Figure 11.

Referring more particularly to the drawings, (a) indicates an assembly or crown of wings or propeller blades, positioned longitudinally to the shaft or axis (k) of the wing-rotor. The blades (a) are held in position by lateral circular discs (b), which are either soldered or welded to the blades. The parts (a) and (b) may be forged or cast in one piece. The inner rigid plane (c) and the axis (k) may also be welded or soldered 10

together or cast or forged as one piece. The outer rigid plane (d) is thickened at its anterior end at (d') and recedes near its posterior end at (d'') from the outer circumference of the crown of wings in order to resume its former position at 15

the very end of its posterior part. The outer rigid plane may be attached to the body (e) of the vessel by means of screws or joints, or otherwise, indicated by the character (f) in Figure 3. It may also be held in position by means of stays or 20

the like connected to the axis (k) (see Figure 2, character (d)). The wing-crown (a) and (b) rotates freely around the axis (k) and the inner rigid plane (c) by means of ball bearings shown 25

in Figure 3, by character (g). A pendulum (o) is connected to the axis (k) in such a manner that 30

it will tend to stabilize the inner rigid plane (c), whenever it is out of its normal position. The upper shaft of this pendulum passes through the axis (k). q represents a joint and p the fulcrum. 35

It may be readily seen how the pendulum functions from Figures 3, 4, 5 and 6. Figure 3 showing the pendulum in position attached to the axis (k) and the body (e) of the flying vessel, and Figures 4, 5 and 6 showing a cross-sectional view of 40

the pendulum in normal position and at a negative and positive angle. The character w represents a wing-rotor. A dynamo (r) attached to the body (e) of the flying vessel is connected to 45

a wheel (s) engaging the lateral end disc (b) of the rotor, by means of a driving shaft (s'). This wheel (s) may act as a brake to reduce the number of revolutions of the wing rotor, or it may be used to drive the wing-rotor by means of the

dynamo, the latter being used as a motor. The propeller of the flying vessel is marked (h). When a vessel of the gyro type is equipped with 50

wing-rotors as shown in Figures 11 and 12, the rotors are rotated horizontally around a vertical axis (i), which is engaged by a shaft (t) by means of gears (t'). The shaft (t) is driven by the motor driving the propeller (h) of the flying vessel or by any other motor of the vessel. The

characters x and x'-x'' indicate the flow of air.

When the wing rotors are in operation, e.g., 55

when the flying vessel is in motion, the air current produced by the forward motion of the flying vessel will engage the blades (a) of the wing-rotor as indicated in Figures 7, 8, 9 and 10. The inner 5 rigid plane (c) will prevent the on-rushing head wind from penetrating into the spaces between the blades (a) which happen to be passing through the upper radius of the wing rotor, and the outer rigid plane (d) will prevent any air from 10 pressing down into these spaces especially while the vessel is ascending.

These two rigid planes eliminate all resistance to lift and forward motion of the vessel.

The arrows clearly indicate the flow of air. 15 The air flow indicated at x'' is forced through the center of the rotor where it is compressed due to the narrowing of the channel and will thus exert a lifting power by pressing upward against the blades which happen to be in the position of 20 the blades characterized by the numerals (1) and (2). The air striking the vessel above blade 1 will pass over the surface of the outer upper rigid plane as indicated by line marked (x'). Due to the outward bend at (d'') the flow of this current 25 of air is finally directed towards the anterior part of the wing rotor thus increasing the forward thrust of the vessel. It will be noted that the blades of the rotors are curved in such a way that the blades exposed to the air current in the lower 30 section of the rotor receive the air on their concave surface, moving with the air-current, while those in the upper section, moving in a direction opposite to the on-rushing air current, present their convex side toward the air current. The 35 direction in which the air vessel moves is indicated by an arrow marked (z).

Any number of wing rotors may be used in series. In Figure 10 the flow of air through two rotors, one behind the other, is clearly illustrated 40 by the lines x and x'-x'', and needs no further explanation.

In order that the wing-rotor may not rotate at a rate where the blades (a) would interfere with the on-rushing air current a brake (s) connected 45 to a dynamo (r) by means of a transmission rod (s') is provided. The excess of power may be used for other purposes. This dynamo may also be used as a motor in order to increase the number of revolutions of the rotors.

50 It is understood that the wing-rotors on either side of the flying vessel may be operated independently so that stabilization may be effected and rolling or banking avoided. One or several rotors on one side of the vessel may have the rigid inner plane at an angle favoring lift, while the corresponding rotor or rotors on the opposite side of the vessel may have the inner rigid plane at an angle favoring descent.

The function of the pendulum (o) is to stabilize 60 the flying vessel in fore and aft direction by operation or maintaining the inner rigid planes (c). If the plane (c) is in an inclined position, positive or negative, as in Figures 5 and 6, the pendulum will tend to resume the position shown in Figure 4 and rotate the inner rigid plane (c) until it assumes normal position.

I claim as my invention:

1. In combination with an aircraft body a fixed 70 member extending substantially horizontally transversely of said body, a turbine-like wing rotor surrounding said member and having its axis transversely of said body, blades extending outwardly from said fixed member to the periphery of said rotor and a plane mounted ex-

teriorly of said rotor and substantially covering the upper portion thereof.

2. A device such as that described in claim 1 having in combination lateral circular discs supporting and connected to turbine like rotor blades. 5

3. A device such as that described in claim 1 having an inner rigid plane so constructed that the upper side is stronger curved than the lower side and having the external rigid plane so arranged that the front rim of same is substantially thickened so that the plane fits in circular form over the upper part of the turbine like rotor wheels in such a manner that it fits closely to the rotor blades near its interior part exposed to the attack of the air current while it recedes from the rotor blades towards its end in order to turn sharply again towards the rotor blades at or near its end, as above described and illustrated. 10

4. An arrangement of wing rotors such as described in claim 1 where a number of wing rotors are arranged in series one behind the other parallel to each other and facing the direction of the current of air in the direction in which the vessel moves. 20

5. A device such as described in claim 1 driven by the air current set up by the moving vessel where the wings may rotate at a speed differing from that normally produced by said air current. 25

6. A device as claimed and described in claim 1, having a wing rotor on each side of the body, the member of each rotor independently movable in opposite directions, for stabilizing purposes. 30

7. A device such as described in claim 1, where- 35 in the rotors are driven against the air by means of a propeller or propellers or any suitable vehicle, whereby the air-current necessary for the rotation of the wing rotors is created.

8. A device such as claimed in claim 1 wherein 40 the wing rotor is driven by the air current set up by the moving vessel where the wings may rotate at a speed differing from that normally produced by said air current having in combination a dynamo so connected with the rotor as 45 to act as a brake in order to reduce the number of revolutions of the rotor.

9. A device as claimed in claim 1, wherein the wing rotor is driven by the air current set up by the moving vessel where the wings may rotate 50 at a speed differing from that normally produced by said air current having in combination a dynamo so connected with the rotor as to act as a brake in order to reduce the number of revolutions of the rotor and having in combination a rotor or rotors coupled with a dynamo. 55

10. A device such as described in claim 1, wherein the wing rotor is driven by the air current set up by the moving vessel where the wings may rotate at a speed differing from that normally produced by said air current having in combination a dynamo so connected with the rotor device as to act as a power device to drive the rotor device. 60

11. In combination with an aircraft body, a 65 vertical, power-driven rotating shaft provided at each side of the body, a plurality of rotor devices mounted on each shaft, the rotor devices consisting of a member mounted on and transversely of said shaft, turbine-like wing rotors 70 surrounding said member, blades extending outwardly from said member to the periphery of said rotor and a plane mounted exteriorly of said rotor and substantially covering the upper part thereof.

12. In combination with an aircraft body, a 75

vertical, power-driven shaft provided at each side of the body, a plurality of rotor devices mounted on each shaft, each rotor device including a member mounted on and transversely of said shaft, turbine-like wing rotors surrounding said member, blades extending outwardly from said member to the periphery of said rotor and a plane mounted exteriorly of said rotor and substantially covering the upper portion thereof, the rotor devices being so arranged that they are driven by said shaft in a direction opposite to the flow of air.

13. In combination with an aircraft body, a vertical shaft provided at each side of the body, a plurality of rotor devices mounted on each shaft, each rotor device including a member mounted on and transversely of said shaft, turbine-like wing rotors surrounding said member, blades extending outwardly from said member to the periphery of said rotor and a plane mounted exteriorly of said rotor and substantially covering the upper portion thereof, wherein the rotor devices are driven against the air by means of a propeller or propellers or any suitable vehicle, whereby the air current necessary for the rotation of the wing rotors is created.

14. In combination with an aircraft body, a fixed member extending substantially horizontally transversely of said body, a turbine-like wing rotor surrounding said member and having its axial transversely of said body, blades extending

outwardly from said fixed member to the periphery of said rotor and a plane mounted exteriorly of said rotor and substantially covering the upper portion thereof, said member constructed with an upper side strongly curved and a lower side practically flat and presenting a profile of substantially semi-circular form.

15. A wing rotor such as described in claim 14, characterized in that said member together with said plane mounted exteriorly of the rotor and covering substantially the upper portion of said rotor are so arranged and constructed that a definite number of air-pockets are formed preventing the flow of air therethru.

16. A device such as described in claim 1, said member constructed with an upper side strongly curved and having the external rigid plane so arranged that the front rim of same is substantially thickened that the plane fits in circular form over the upper part of the turbine-like rotor wheels in such a manner that it fits closely to the rotor blades near its interior part exposed to the attack of the air current while it recedes from the rotor blades at or near its end, characterized in that the said inner rigid plane is movable over its axis in such a way as to prevent the current of air rushing thru a selected number of the rotor wheels, as above described and illustrated.

JOHANNES CHRISTIANSEN.
